UNITED STATES PATENT OFFICE.

JOHN P. WEIS, OF NYACK, NEW YORK, ASSIGNOR TO LUCIUS N. LITTAUER, OF GLOVERSVILLE, NEW YORK.

FEED MECHANISM FOR SEWING-MACHINES.

1,242,403.

Specification of Letters Patent. Patented Oct. 9, 1917.

Application filed February 23, 1916. Serial No. 79,836.

To all whom it may concern:

Be it known that I, JOHN P. WEIS, a citizen of the United States, residing at Nyack, in the county of Rockland and State of New York, have invented certain new and useful improvements in Feed Mechanism for Sewing-Machines, of which the following is a specification.

This invention relates to sewing machines, and more particularly, to top and bottom four-motion feeding mechanisms for sewing machines, the object of the invention being to provide a feeding mechanism, which will feed the top and bottom plies of material past the stitching mechanism at a uniform speed, so that the ends of the material will be even after the stitching is completed, and also to provide a mechanism, which will enable the operator to follow irregular lines, such as stitching around sharp corners or curves of a small radius, as the fingers of gloves and the like. The invention is also useful in stitching what is known in the trade as piping, used in the manufacture of fancy shoes, which are at present in vogue. The requirements for such work necessitate a very compact top feeding mechanism to take up as little space around the needle as possible, and the mechanism must be entirely out of the way of the operator's fingers to permit the rapid handling of the work, and it is also essential that a clear vision of the line of seam directly at the needle point be had, also that the needle and presser finger be as small as possible so that the work may be turned quickly while the machine is in motion and during the time that the feeds are free from the work. The organization and operation of the feeding elements, in the present improvement are such that when the needle is out of the work the bottom feed is above the throat plate, so as to lift the work clear of the same, while the top feed is down on top of the work and holds it so that the movement of both feeds advances the work at a uniform speed. Prior to the top and bottom feeds leaving their grip on the work, a presser finger is brought into engagement with the top of the work to hold it against the throat plate while the needle is in the work, such finger remaining in this position until the top feed rises, the bottom feed falls and they both move forward to again shift into position

for the next feeding stroke, at which time 55 the presser finger is lifted to permit the feeding of the work. From this, it will be readily understood that as the presser finger has a very small surface in contact with the work, it may be freely turned while the machine is in motion, so that irregular lines 60 may be followed with facility.

In the drawings accompanying and forming part of this specification, Figure 1 is a rear view of the machine and shows the 65 driving mechanism for giving the feed movements to the top feed; Fig. 2 is a sectional end view looking in the direction of the arrow in Fig. 1 with parts of the frame broken away clearly to show operative parts of the 70 top and bottom feed mechanism; Fig. 3 is a sectional view of the head end of the machine looking from the front side thereof; Fig. 4 is an end view similar to Fig. 2 but showing the feeding mechanism and the needle 75 in a different position; Fig. 5 is a detail perspective view of a portion of the top feeding mechanism and the needle operating means with a part of the presser finger mechanism detached and shown to the right 80 thereof; Fig. 6 is a detail sectional view of the spring barrel for giving pressure to either the presser finger or the top feed; Fig. 7 is a cross sectional view taken on the line 7—7 of Fig. 3, and looking in the direction of the arrow in said figure; Fig. 8 is a rear end view of a portion of the machine and illustrates the top feed actuating 85 means; and Fig. 9 is a detail sectional view of the looper operating means taken on the line 9—9, Fig. 3.

Similar characters of reference indicate corresponding parts in the several figures.

The improvements are shown applied to what is known as a Metropolitan top and 95 bottom rotary shaft machine, but the invention may be used with other types of machine by simple modifications and, therefore, but a brief description of such a machine is deemed necessary.

The machine base 1, has the usual cloth plate 2, the vertical portion 3, and the top or overhanging arm 4, terminating in the head 28. The base carries the rotary shaft 5 operating in suitable bearings thereof, while the top arm carries the rotary shaft 6 hereinafter referred to as a top shaft or top driving shaft, also operating in suitable 105

bearings. These shafts 5 and 6 are connected for rotary motion by the crank connections 7. Any well known form of stitching mechanism may be employed, but I have shown a well known form of the Metropolitan stitching mechanism, comprising an eccentric 8 secured to the bottom shaft 5, see Figs. 1 and 9, having a strap connection 9 connected at 10 to the crank arm 11, secured 10 to the looper shaft 12 so as to rock said looper shaft in its bearings 13. A bevel gear 14 also secured to the shaft 5 co-operates with a similar gear 15 and constitutes a right angle drive to operate a shaft 16. 15 This shaft 16 has a crank portion 16', on which is located a split block 17' (see Fig. 3). This split block fits between parallel members 17 secured to the looper shaft 12 and these parallel members therefore form a 20 fork for the split block 17'. When the shaft 16 is rotated by the bevel gear the crank 16' also rotates and therefore shifts the split block 17', which in turn shifts the fork 17 secured to the looper shaft and thereby 25 shifts the looper shaft lengthwise, or endwise in its bearings 13, so that the looper 18 thus has the usual four motions, so as to take a loop of thread from the needle on one side and deliver a loop of looper thread at 30 the other side thereof in the formation of a double chain stitch. This looper 18 is carried in the looper holder 19, which is secured to the looper shaft 12. The needle actuating means comprises a crank disk 20 secured to the top shaft 6, and carries a crank pin 21, on which a pitman 22 is mounted, so as to reciprocate vertically the needle bar 23 to which it is attached as at 24. This connection 24 is provided with an extended portion 25, which slides in the way 25' of the head, see Fig. 3, to guide the needle bar and prevent axial movement thereof. The needle bar 23 passes through and reciprocates in a 40 sliding bushing 26, which in turn slides in a bushing 27 fixed in the head 28 of the top arm 4, and this needle bar 23 is provided with a needle chuck 29 to hold the needle 30. The needle is so timed as to co-operate with the looper in the well known manner. 45

50 The bottom feed mechanism is of the well known Metropolitan construction and will likewise be described only briefly. The base 1 is provided with bearings 31, see Figs. 1, 2 and 7, bored to receive the rock shaft 32 which pivotally supports the rocker frame 33 carrying a shaft 34 at the top thereof. This shaft is secured to one end of a connection 35 which is operated by the adjustable crank generally indicated by 36, carried by a disk 37 secured to the end of the main shaft 5. A feed lift eccentric 38 is also secured to the main shaft 5 and operates to lift the feed bar 39, to which a feed dog 40 is secured. This bar 39 has an extended portion reaching back and connected

with the shaft 34, as at 41, between the two hubs 42 of the rocker frame 33. An angle member 43, carried by the feed bar 39, contacts with the eccentric 38, so that the rise and fall movement of the feed bar and dog 40 at any speed is positive. The top feed mechanism comprises a disk 44, see Fig. 8, secured to the end of the top shaft 6, and has an adjustable crank 45 secured thereto having a connection 46, with its other end connected as at 47 to a slide block 48, shiftable on a curved arm 49, thereby to instantaneously vary the stroke of the top feed. When adjusted to the desired stroke, a clamping screw 50 may be tightened to prevent movement of the block 48. A stop 51 is provided in the top of the curved arm 49 to limit the movement of the block 48 in that direction. The top arm 4 is provided with bearings 52 and 53 for a rock shaft 54, and the curved arm 49 is secured to the rock shaft, as at 55. A depending arm 56 is secured to the other end of the rock shaft and the lower end of this depending arm 56 has pivotally secured thereto a link 57, which connects with a top feed bar 58, swinging on a pivot 59 carried by a slotted bushing 60, secured in the top of the machine head 28. The top of this feed bar 58 is slotted at 61 for vertical movement, relative to its pivot 59 to compensate for varying thickness of material. The link 57 gives the feeding stroke to the top feed dog. About midway of the length of the feed bar 58 is a projecting lug 62, pivotally secured to a plunger or piston 63, carrying a pin 64 working in a slot 65 of a barrel or casing 66, which has a threaded nut 67 to close its top and provide a bearing for the stem 68 of the plunger 63. A spring 69 is located in the barrel to give pressure to the plunger 63, and this pressure is transmitted by means of the feed bar 58 to the top feed dog 70 secured as at 71 to the bottom of the feed bar 58. This top feed 70 may be provided with feed teeth 72 if desired, but for the stitching of leather, practice has shown that the teeth are injurious to such material and smooth surfaces on the top and bottom feed are preferred 115 for that class of work. The needle driving crank pin 21 carries a crank arm 74, having a hub 75, carrying a pin 76, see Fig. 5, which projects through an ear 77 of the barrel 66, thereby to give the rising and 120 falling movements to the top feed. This pin 76, is provided with a crank arm 78 which carries a shoulder screw 79, to which is connected for free movement a barrel, or casing 80, also having a coiled spring 81 125 therein. This barrel is similar to the spring barrel 66, and therefore also has a pin and slot connection 64', except that the plunger or piston 82 therein has an extended portion 83 reaching down and connecting as at 130

82' to the sliding bushing 26. A collar 84 is secured to the lower end of this bushing 26 and this collar carries a vertical piece 85, which serves to strengthen the construction 5 at the screw connection 82'. The collar 84 is so shaped that it will receive the shank 86 of the presser finger, so that the same can be vertically adjusted. This shank is attached to the collar 84 at an angle so as to permit free access to its attaching means for ready adjustment thereof. The presser finger is reduced in width as at 87, see 10 Figs. 2 and 3, and is so shaped as to fit close to the needle and has a bottom portion 88 in position to press on the work, and which part 88 is so shaped as to work in the slot 89 of the top feed 70. It will be observed that this presser finger receives its rising and falling movement from the 15 top driving shaft through the medium of the piston 82 and its casing or barrel 80, and that the top feed 70 also receives its rising and falling movements from the same top shaft through the medium of a piston 63 20 and its casing or barrel 66, while the to-and-fro or feed movements of the top feed are obtained from the rock shaft through its connection with the top shaft and its connections, including the link 57, with the 25 feed bar 58.

On account of the peculiar construction and mode of operation of the top feed mechanism, the needle bar operates in a single bearing and as the triple crank connections 30 21 and 76 would interfere with an upwardly extended needle bar, it is, therefore, only of sufficient length to connect at 24 with its pitman 22. As, heretofore the needle threads are usually partly under the control of the upper end of the needle bar and as it has been found by long practice that such thread control is very satisfactory, that is to say the movement of the needle bar has been utilized as a common take-up 35 40 for the top threads, therefore, to obtain the same effect with this short needle bar, I have provided a wire thread carrier 90, operating in a bushing 91, secured in the machine head 28, and this thread carrier extends down into the machine head as at 92, 45 and is connected as at 93 with the needle bar driving means for vertical reciprocation with the needle bar. Thus it will be seen that a very light thread handling means 50 is provided as a substitute for the usual long needle bar and it is capable of high speed and is free from noise.

Two means of raising the top feed and presser finger from the work are provided, 55 one to be operated by foot and the other by hand. A rod 94, carrying a coiled spring and collar 95 extends down through the machine base and is connected with a floor treadle, (not shown) to be operated by the 60 foot of the operator. This rod connects, as

at 96, with a lever 97 pivotally secured to the machine arm 4 as at 98. This lever has its other end 99 in position to engage an angle rod 100, carried by the lifter guide piece 101, see Fig. 4, which operates in a slot 70 102, see Fig. 1 of the head 28. This guide piece is adjustably secured as at 103 to the top feed bar 58. The usual hand lifter 104 also operates in this slot 102 to lift the top feed by hand when desired and hold it in 75 that position for any length of time, the foot lifting means being more generally used for rapid operation.

It will thus be seen from the foregoing that if the machine is started up at speed 80 while either of the top feeds is in engagement, the action of the cranks is absorbed by the springs located in the spring-barrels and the pins 64 and 64' which slide in their slots freely so that no damage will result, 85 this mechanism thus forming a shock absorbing means.

It will be observed from the foregoing that the organization of the parts is such that the mode of operation set forth in that 90 part of the description preceding the description of the figures of the drawings takes place, so that it is unnecessary to again repeat this matter.

It will also be understood that the various 95 details may be more or less changed without departing from the scope or spirit of this improvement.

I claim as my invention:

1. In a sewing machine, the combination 100 of a rotary top driving shaft, feeding mechanism comprising a bottom and a top feed and means for operating them, a presser finger of relatively small dimensions, said top feed and presser finger having pivotal 105 connection with the top driving shaft through the same crank pin, the means for operating the feeding mechanism and the presser finger being so organized that the presser finger may remain in engagement 110 with the work when the top and bottom feeds are out of engagement therewith whereby the free turning of the work when the presser finger is in engagement therewith may be effected.

2. In a sewing machine, the combination 115 of a rotary top driving shaft, feeding mechanism comprising a bottom and a top feed and means for operating them, a presser finger of relatively small dimensions, said top feed and presser finger having pivotal 120 connection with the top driving shaft through the same crank pin, the means for operating the feeding mechanism and the presser finger being so organized that the 125 presser finger may remain in engagement with the work when the top and bottom feeds are out of engagement therewith whereby the free turning of the work when the presser finger is in engagement therewith 130

may be effected, said top feed having a slot and said presser finger working therethrough.

3. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the top feed including a spring-pressed piston and a crank-connected casing.

4. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, said top feed having a slot and said presser finger working therethrough, the operating means for the top feed including a spring-pressed piston and a crank-connected casing.

5. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the presser finger including a spring-pressed piston and a crank-connected casing.

6. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, said top feed having a slot and said presser finger working there-

through, the operating means for the presser finger including a spring-pressed piston and a crank-connected casing.

7. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the top feed and the presser finger including a pair of spring-pressed pistons and a pair of crank-connected casings.

8. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, said top feed having a slot and said presser finger working therethrough, the operating means for the top feed and the presser finger including a pair of spring-pressed pistons and a pair of crank-connected casings.

9. In a sewing machine, the combination of a rotary top driving shaft, feeding mechanism comprising a bottom and a top feed and means for operating them, a presser finger of relatively small dimensions, said top feed and presser finger having pivotal connection with the top driving shaft through the same crank pin, the means for operating the feeding mechanism and the presser finger being so organized that the presser finger may remain in engagement with the work when the top and bottom feeds are out of engagement therewith whereby the free turning of the work when the presser finger is in engagement therewith may be effected, the operating means for the top feed including a rock shaft and a shiftable sliding block connected with said top driving shaft.

10. In a sewing machine, the combination of a top driving shaft, a rock shaft connected therewith, a four-motion top feed connected with said top driving shaft and rock shaft, and a presser finger also connected with the top driving shaft and having part of the motions of said top feed, the connecting means between the top feed and the driving shaft and between the presser finger

and the driving shaft each including a spring-actuated member.

11. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the top feed including a spring-pressed piston and a crank-connected casing and also including a rock shaft and a shiftable sliding block.

12. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the presser finger including a spring-pressed piston and a crank-connected casing and the operating means for the top feed including a rock shaft and a shiftable sliding block.

13. In a sewing machine, the combination of feeding mechanism comprising a bottom and a top feed and means for operating them, a presser finger of relatively small dimensions, and means for operating it, the operating means for the feeding mechanism and the presser finger being so organized that the presser finger may remain in engagement with the work when the top and bottom feeds are out of engagement therewith whereby the free turning of the work when the presser finger is in engagement therewith may be effected, the operating means for the top feed and the presser finger including a pair of spring-pressed pistons and a pair of crank-connected casings and the operating means for the top feed also including a rock shaft and a shiftable sliding block.

14. In a sewing machine, the combination of a top driving shaft, a rock shaft, means connecting said rock shaft with said top driving shaft and including a shiftable sliding block, feeding mechanism including a top feed connected with said rock shaft and also with said top driving shaft, and a presser finger also connected with said top driving shaft for reciprocation thereby, each of said

connections with the top driving shaft including a shock absorbing means.

15. In a sewing machine, the combination of a top driving shaft, a rock shaft, means connecting said rock shaft with said top driving shaft and including a shiftable sliding block, feeding mechanism including a top feed connected with said rock shaft and also with said top driving shaft, and a presser finger also connected with said top driving shaft, the connection between said top feed and its driving shaft including a spring-pressed piston and a crank-connected casing.

16. In a sewing machine, the combination of a top driving shaft, a rock shaft, means connecting said rock shaft with said top driving shaft and including a shiftable sliding block, feeding mechanism including a top feed connected with said rock shaft and also with said top driving shaft, and a presser finger also connected with said top driving shaft, the connection between said presser finger and the top driving shaft including a spring-pressed piston and a crank-connected casing.

17. In a sewing machine, the combination of a top driving shaft, a rock shaft, means connecting said rock shaft with said top driving shaft and including a shiftable sliding block, feeding mechanism including a top feed connected with said rock shaft and also with said top driving shaft, and a presser finger also connected with said top driving shaft, the connection between the top feed and its driving shaft and between the presser finger and the top driving shaft including a pair of spring-pressed pistons and a pair of crank-connected casings.

18. In a sewing machine, the combination of a lower and an upper driving shaft, feeding mechanism including a top feed, and means for operating it and including a spring-pressed piston and a crank-connected casing connected with one of said shafts.

19. In a sewing machine, the combination of feeding mechanism including a top feed, means for operating it and including a spring-pressed piston and a crank-connected casing, and a rock shaft having connection with said top feed.

20. In a sewing machine, the combination of a lower and an upper driving shaft, feeding mechanism including a top feed, and means connecting said top feed with said upper driving shaft and including a spring-pressed piston and a crank-connected casing.

21. In a sewing machine, the combination of feeding mechanism including a top feed, a top driving shaft, means connecting said top feed with said driving shaft and including a spring-pressed piston and a crank-connected casing, and a rock shaft connected with said top feed and with said top driving shaft.

22. In a sewing machine, the combination of a lower and an upper driving shaft, a feed dog, and means connecting said feed dog with said upper driving shaft and including a crank-connected casing.
23. In a sewing machine, the combination of a driving shaft, a feed dog, means connecting said feed dog with said driving shaft and including a crank-connected casing, a rock shaft, and means connecting said rock shaft with said driving shaft and with said feed dog.
24. In a sewing machine, the combination of a lower and an upper driving shaft, a feed dog, and means connecting said feed dog with said upper driving shaft and including a crank-connected casing and a spring-pressed piston.
25. In a sewing machine, the combination of a driving shaft, a feed dog, means connecting said feed dog with said driving shaft and including a crank-connected casing and a spring-pressed piston, a rock shaft, adjustable means connecting said rock shaft with said driving shaft, and means connecting said rock shaft with said feed dog.
26. In a sewing machine, the combination of a driving shaft, a pair of reciprocating members crank-connected with said driving shaft, each having an independent pivotal connection with the crank of said shaft and one extending through the other and having a sliding engagement relatively to each other, and a work-engaging instrumentality connected with each of said sliding members for movement thereby.
27. In a sewing machine, the combination of a driving shaft, a pair of reciprocating members crank-connected with said driving shaft, each having an independent pivotal connection with the crank of said shaft and one extending through the other and having a sliding engagement relatively to each other, a work-engaging instrumentality connected with each of said sliding members for movement thereby, and a spring coöperating with one of said sliding members.
28. In a sewing machine, the combination of a driving shaft, three reciprocating members crank-connected with said driving shaft, a pair thereof extending one through the other and having a sliding engagement relatively to each other, a work-engaging instrumentality connected with each of said members for movement thereby, means for pivotally supporting one of said members, and means for imparting a to-and-fro movement to said pivotally supported member.
29. In a sewing machine, the combination of a driving shaft, three reciprocating members crank-connected with said driving shaft, a pair thereof extending one through the other and having a sliding engagement relatively to each other, a work-engaging instrumentality connected with each of said mem-
- bers for movement thereby, means for pivotally supporting one of said members, and means for imparting a to-and-fro movement to said pivotally supported member and including a rock shaft connected with said driving shaft.
30. In a sewing machine having a throat plate, the combination of a bottom feed effective to lift the work above and clear of the throat plate when the needle is out of the work, a top feed coöperating with the bottom feed to hold the work so that the work will be advanced at a uniform speed by said top and bottom feeds, a presser finger effective to engage the top of the work prior to the top and bottom feeds leaving their grip on the work and while the needle is in the work to hold it against the throat plate, said presser finger maintaining such holding position until the feeding movement of the top and bottom feed, and means for actuating the top and bottom feed and presser finger, the foot of the presser finger constructed of a size and shape to permit the free turning of the work while such presser finger is in engagement therewith and the feeds are free thereof, substantially as described.
31. In a sewing machine, the combination of a pair of work-engaging instrumentalities one comprising a feed dog and the other a presser finger, a top driving shaft, means connecting said top driving shaft with said instrumentalities and comprising a pair of crank-connected members each comprising a pair of members having a sliding engagement relatively to each other whereby a rising and falling movement is imparted to said instrumentalities, and means for imparting to said feeding instrumentality a to-and-fro movement.
32. In a sewing machine, the combination of a pair of work-engaging instrumentalities one comprising a feed dog and the other a presser finger, a top driving shaft, means connecting said top driving shaft with said instrumentalities and comprising a pair of crank-connected members each comprising a pair of members having a sliding engagement relatively to each other whereby a rising and falling movement is imparted to said instrumentalities, and means for imparting to said feeding instrumentality a to-and-fro movement and comprising a rock shaft connected with said top driving shaft.
33. In a sewing machine, the combination of a pair of work-engaging instrumentalities one comprising a feed dog and the other a presser finger, a top driving shaft, means connecting said top driving shaft with said instrumentalities and comprising a pair of crank-connected members each comprising a pair of members having a sliding engagement relatively to each other whereby a rising and falling movement is imparted to

- 5 said instrumentalities, and means for imparting to said feeding instrumentality a to-and-fro movement and comprising a rock shaft having an adjustable connection with said driving shaft, said connection including a sliding block. 70
- 10 34. In a sewing machine, the combination of a work-engaging instrumentality, a rotary top driving shaft, a spring-pressed piston connected with said top driving shaft, and means supporting said instrumentality and pivotally connected to said piston. 75
- 15 35. In a sewing machine the combination of a pair of work-engaging instrumentalities, one a presser finger and the other a feed dog, a driving shaft, and a spring pressed piston pivotally connected to each of said instrumentalities and also connected to said driving shaft. 80
- 20 36. In a sewing machine, the combination of a pair of work-engaging instrumentalities one a presser finger and the other a feed dog, a driving shaft, a spring-pressed piston pivotally connected with each of said instrumentalities and also connected to said driving shaft, and means for imparting a to-and-fro movement to said feed dog. 85
- 25 37. In a sewing machine, the combination of a pair of work-engaging instrumentalities one a presser finger and the other a feed dog, a driving shaft, a spring-pressed piston pivotally connected with each of said instrumentalities and also connected to said driving shaft, means for imparting a to-and-fro movement to said feed dog, and means for pivotally supporting said feed dog independently of its connection with said driving shaft. 90
- 30 38. In a sewing machine, the combination of a pair of work-engaging instrumentalities one a presser finger and the other a feed dog, a driving shaft, a spring-pressed piston pivotally connected with each of said instrumentalities and also connected to said driving shaft, means for pivotally supporting said feed dog for rising and falling movement independently of said driving shaft, and means for lifting said feed dog. 95
- 35 39. In a sewing machine, the combination of a pair of work-engaging instrumentalities one a presser finger and the other a feed dog, a driving shaft, a spring-pressed piston pivotally connected with each of said instrumentalities and also connected to said driving shaft, means for pivotally supporting said feed dog for rising and falling movement independently of said driving shaft, and a pair of independent means for lifting said feed dog. 100
- 40 40. In a sewing machine, the combination of a driving shaft, a feed dog, a pair of sliding members pivotally connected with said feed dog and crank-connected with said shaft, and means for lifting said feed dog. 105
- 45 41. In a sewing machine, the combination of a driving shaft, a feed dog, a pair of sliding members pivotally connected with said feed dog and crank-connected with said shaft, and a pair of means for lifting said feed dog. 110
- 50 42. In a sewing machine, the combination of a bottom feed, a top feed and a presser foot, and a top driving shaft, said top feed and presser foot having the same pivotal connection with said top driving shaft. 115
- 55 43. In a sewing machine, the combination of a top feed and a presser finger, a top driving shaft, and a pair of similarly formed means for imparting rising and falling movements to said top feed and presser finger. 120
- 60 44. In a sewing machine, the combination of a top feed and a presser finger, a top driving shaft, and duplicate means for imparting rising and falling movements to said top feed and presser finger and comprising a pair of spring-pressed pistons and crank-connected casings carrying said pistons. 125
- 65 45. In a sewing machine, the combination of a top feed and a presser finger, a top driving shaft, a pair of similarly formed shock absorbing means for imparting rising and falling movements to said top feed and presser finger, and means for imparting a to-and-fro movement to said top feed. 130
- 70 46. In a sewing machine, the combination of a top feed and a presser finger, a top driving shaft, duplicate means for imparting rising and falling movements to said top feed and presser finger and comprising a pair of spring-pressed pistons and crank-connected casings carrying said pistons, and means for imparting a to-and-fro movement to said top feed. 135
- 75 47. In a sewing machine, the combination of a top feed and a presser finger, a driving shaft, means for imparting rising and falling movements to said top feed, means for imparting rising and falling movements to the presser finger, each of said means including means for absorbing the shock on the starting of the machine at speed when either the top feed or presser finger is in engagement with the work and means for imparting a to-and-fro movement to said top feed. 140
- 80 48. In a sewing machine, the combination of a top feed and a presser finger, a top driving shaft, duplicate means for imparting rising and falling movements to said top feed and presser finger and comprising a pair of spring-pressed pistons and crank-connected casings carrying said pistons, and means for imparting a to-and-fro movement to said top feed and comprising a rock shaft connected with said top driving shaft. 145
- 85 49. In a sewing machine, the combination of a pair of driving shafts, feeding mechanism comprising a bottom and a top feed each receiving its motion from one of said 150

- shafts, a needle reciprocated from one of said shafts, a presser finger also reciprocated from one of said shafts, the top feed, the presser finger and the needle all being operated by the same shaft, means also operative from the same shaft for imparting a to-and-fro movement to the top feed, the organization being such that the presser finger will engage the work when the top and bottom feeds are disengaged therefrom thereby to permit the work to be readily turned while the needle is in the work and the presser finger disengaged from the work while the feeds are in engagement therewith, the operating means for the presser finger and top feed including means for absorbing the shock on the starting of the machine at speed when the top feed or presser finger is in engagement with the work.
20. 50. In a sewing machine, the combination of a pair of driving shafts, feeding mechanism comprising a bottom and a top feed each receiving its motion from one of said shafts, a needle reciprocated from one of said shafts, a presser finger also reciprocated from one of said shafts, the top feed, the presser finger and the needle all being operated by the same shaft, and means also operative from the same shaft for imparting a to-and-fro movement to the top feed, the organization being such that the presser finger will engage the work when the top and bottom feeds are disengaged therefrom thereby to permit the work to be readily turned while the needle is in the work and the presser finger disengaged from the work while the feeds are in engagement therewith, the connecting means between said top feed and presser finger including a pair of spring-pressed pistons and casings crank-connected with the driving shaft and the means for imparting the to-and-fro movement from the top feed mechanism comprising a rock shaft connected with the top feed and adjustably connected with the driving shaft through the medium of a sliding block.
30. 51. In a sewing machine, the combination of a pair of driving shafts, feeding mechanism comprising a bottom and a top feed each receiving its motion from one of said shafts, a needle reciprocated from one of said shafts, a presser finger also reciprocated from one of said shafts, the top feed, the presser finger and the needle all being operated by the same shaft, and means also operative from the same shaft for imparting a to-and-fro movement to the top feed, the organization being such that the presser finger will engage the work when the top and bottom feeds are disengaged therefrom thereby to permit the work to be readily turned while the needle is in the work and the presser finger disengaged from the work while the feeds are in engagement therewith, the connecting means between said top feed and presser finger including a pair of spring-pressed pistons and casings crank-connected with the driving shaft.
35. 52. In a sewing machine, the combination of a pair of driving shafts, feeding mechanism comprising a bottom and a top feed each receiving its motion from one of said shafts, a needle reciprocated from one of said shafts, a presser finger also reciprocated from one of said shafts, the top feed, the presser finger and the needle all being operated by the same shaft, and means also operative from the same shaft for imparting a to-and-fro movement to the top feed, the organization being such that the presser finger will engage the work when the top and bottom feeds are disengaged therefrom thereby to permit the work to be readily turned while the needle is in the work and the presser finger disengaged from the work while the feeds are in engagement therewith, the connecting means between said top feed and presser finger including a pair of spring-pressed pistons and casings crank-connected with the driving shaft and the means for imparting the to-and-fro movement from the top feed mechanism comprising a rock shaft connected with the top feed and adjustably connected with the driving shaft through the medium of a sliding block.
40. 53. In a sewing machine, the combination of a feed member, a needle, a presser finger, and a top driving shaft crank-connected with all of said elements for imparting a rising and falling movement to each thereof, said connection with the feed member and presser finger including a shock absorbing means.
45. 54. In a sewing machine, the combination of a feed member, a needle, a presser finger, a top driving shaft crank-connected with all of said elements for imparting a rising and falling movement to each thereof, said connection with the feed member and presser finger including a shock absorbing means, and means for imparting a to-and-fro movement to the feed member.
50. 55. In a sewing machine, the combination of a feed member, a needle, a presser finger, a top driving shaft crank-connected with all of said elements for imparting a rising and falling movement to each thereof, said connection with the feed member and presser finger including a shock absorbing means, and means for imparting a to-and-fro movement to the feed member and comprising a rock shaft connected to said top driving shaft.
55. 56. In a sewing machine, the combination of a feed member, a needle, a presser finger, a top driving shaft crank-connected with all of said elements for imparting a rising and falling movement to each thereof, and means for imparting a to-and-fro move-

ing a rock shaft connected with the top feed and adjustably connected with the driving shaft.

60. 52. In a sewing machine, the combination of a pair of driving shafts, feeding mechanism comprising a bottom and a top feed each receiving its motion from one of said shafts, a needle reciprocated from one of said shafts, a presser finger also reciprocated from one of said shafts, the top feed, the presser finger and the needle all being operated by the same shaft, and means also operative from the same shaft for imparting a to-and-fro movement to the top feed, the organization being such that the presser finger will engage the work when the top and bottom feeds are disengaged therefrom thereby to permit the work to be readily turned while the needle is in the work and the presser finger disengaged from the work while the feeds are in engagement therewith, the connecting means between said top feed and presser finger including a pair of spring-pressed pistons and casings crank-connected with the driving shaft and the means for imparting the to-and-fro movement from the top feed mechanism comprising a rock shaft connected with the top feed and adjustably connected with the driving shaft through the medium of a sliding block.

65. 53. In a sewing machine, the combination of a feed member, a needle, a presser finger, and a top driving shaft crank-connected with all of said elements for imparting a rising and falling movement to each thereof, said connection with the feed member and presser finger including a shock absorbing means.

70. 54. In a sewing machine, the combination of a feed member, a needle, a presser finger, a top driving shaft crank-connected with all of said elements for imparting a rising and falling movement to each thereof, said connection with the feed member and presser finger including a shock absorbing means, and means for imparting a to-and-fro movement to the feed member.

75. 55. In a sewing machine, the combination of a feed member, a needle, a presser finger, a top driving shaft crank-connected with all of said elements for imparting a rising and falling movement to each thereof, said connection with the feed member and presser finger including a shock absorbing means, and means for imparting a to-and-fro movement to the feed member and comprising a rock shaft connected to said top driving shaft.

80. 56. In a sewing machine, the combination of a feed member, a needle, a presser finger, a top driving shaft crank-connected with all of said elements for imparting a rising and falling movement to each thereof, and means for imparting a to-and-fro move-

ment to the feed member and comprising a rock shaft connected to said top driving shaft, said connection including a sliding block.

5 57. In a sewing machine, the combination of a feed member, a needle, a presser finger, a top driving shaft crank-connected with all of said elements for imparting a rising and falling movement to each thereof, said 10 connection with the feed member and presser finger including a shock absorbing means, means for imparting a to-and-fro movement to the feed member and comprising a rock shaft connected to said top driving shaft, and means for raising and lowering said feed member.

20 58. In a sewing machine, the combination of a feed member, a needle, a presser finger, a top driving shaft, and means connecting one or more of said elements with said top driving shaft and including a piston-actuated member.

25 59. In a sewing machine, the combination of a feed member, a needle, a presser finger, a top driving shaft, and means connecting one or more of said elements with said top driving shaft and including a spring-pressed piston-actuated member.

30 60. In a sewing machine, the combination of a feed member, a needle, a presser finger, a top driving shaft, and means connecting one or more of said elements with said top driving shaft and including a piston-actuated member crank-connected with said shaft.

35 61. In a sewing machine, the combination of a top driving shaft, a feed member, a needle, and a presser finger, all connected with said top driving shaft, the connection of the feed member and presser finger including a spring-pressed member crank-connected with said shaft.

40 62. In a sewing machine, the combination of a top driving shaft, a feed member, a needle, and a presser finger all connected with said top driving shaft, the connection of the feed member and presser finger including a spring-pressed member crank-connected with said shaft, a rock shaft, 45 means connecting the rock shaft with the feed member, and means connecting said rock shaft with the top driving shaft.

45 63. In a sewing machine, the combination of a top driving shaft, a feed member, a needle, and a presser finger all connected with said top driving shaft, the connection of the feed member and presser finger including a spring-pressed member crank-connected with said shaft, a rock shaft, 50 means connecting the rock shaft with the feed member, and means connecting said rock shaft with the top driving shaft and including an adjustable sliding block.

55 64. In a sewing machine, the combination of a top driving shaft, a sliding bush-

ing, a needle bar reciprocating in said bushing and connected with said top driving shaft, a work-engaging instrumentality connected with said sliding bushing, and means independent of the needle bar connecting said sliding bushing with said top driving shaft whereby a rising and falling movement is imparted to said instrumentality. 70

65 65. In a sewing machine, the combination of a top driving shaft, a sliding bushing, a needle bar reciprocating in said bushing and connected with said top driving shaft, a work-engaging instrumentality connected with said sliding bushing, and means connecting said sliding bushing with said top driving shaft whereby a rising and falling movement is imparted to said instrumentality, said connecting means comprising a crank-connected sliding piston. 75 80 85

66. In a sewing machine the combination of a top driving shaft, a sliding bushing, a needle bar reciprocating in said bushing and connected with said top driving shaft, a work-engaging instrumentality connected with said sliding bushing, and means connecting said sliding bushing with said top driving shaft whereby a rising and falling movement is imparted to said instrumentality, said connecting means comprising a spring-pressed crank-connected sliding piston. 90 95

67. In a sewing machine, the combination of a top driving shaft, a sliding bushing, a needle bar reciprocating in said bushing and connected with said top driving shaft, a work-engaging instrumentality connected with said sliding bushing, means connecting said sliding bushing with said top driving shaft whereby a rising and falling movement is imparted to said instrumentality, and a thread guide connected with said needle bar and reciprocating therewith and extending above the top of the shaft. 100 105 110

68. In a sewing machine, the combination of a top driving shaft, a sliding bushing, a needle bar reciprocating in said bushing and connected with said top driving shaft, a work-engaging instrumentality connected with said sliding bushing, means connecting said sliding bushing with said top driving shaft whereby a rising and falling movement is imparted to said instrumentality, said connecting means comprising a crank-connected sliding piston, and a thread guide connected with said needle bar and reciprocating therewith and extending above the top of the shaft. 115 120

69. In a sewing machine, the combination of a top driving shaft, a sliding bushing, a needle bar reciprocating in said bushing and connected with said top driving shaft, a work-engaging instrumentality connected with said sliding bushing, means connecting said sliding bushing with said top driving 125 130

shaft whereby a rising and falling movement is imparted to said instrumentality, said connecting means comprising a spring-pressed crank-connected sliding piston, and

5 5 a thread guide connected with said needle bar and reciprocating therewith and extending above the top of the shaft.

70. In a sewing machine, the combination of a top driving shaft, a reciprocating 10 needle bar having a single support below and connected with said shaft, a sliding member reciprocating relatively to said needle bar, a work-engaging instrumentality carried by said sliding member, and 15 means independent of the needle-bar connecting said sliding member with said driving shaft.

71. In a sewing machine, the combination of a top driving shaft, a reciprocating 20 needle bar having a single support below and connected with said shaft, a sliding member reciprocating relatively to said needle bar, a work-engaging instrumentality carried by said sliding member, means 25 independent of the needle bar connecting said sliding member with said driving shaft, and a thread guide carried by said needle bar and extending above said driving shaft.

30 72. In a sewing machine, the combination of a head having a guiding bushing at its lower end, a sliding bushing therein, a presser finger carried by said sliding bushing, a needle bar reciprocating in said sliding bushing, a top driving shaft located above the top of said needle bar, and independent means connecting said needle bar and said sliding bushing with the top driving shaft.

73. In a sewing machine, the combination 40 of a head having a guiding bushing at its lower end, a sliding bushing therein, a presser finger carried by said sliding bushing, a needle bar reciprocating in said sliding bushing, a top driving shaft located 45 above the top of said needle bar, and independent means connecting said needle bar and said sliding bushing with the top driving shaft, the means connecting the sliding bushing including a crank-connected spring-pressed piston.

74. In a sewing machine, the combination 50 of a head having a guiding bushing at its lower end, a sliding bushing therein, a presser finger carried by said sliding bushing, a needle bar reciprocating in said sliding bushing, a top driving shaft located above the top of said needle bar, independent means connecting said needle bar and said sliding bushing with the top driving 55 shaft, the means connecting the sliding bushing including a crank-connected spring-pressed piston, another crank-connected spring-pressed piston connected with said top driving shaft, a feed bar pivotally supported for rising and falling movement and

connected with said last spring-pressed piston, and means connected with said top driving shaft for imparting a to-and-fro movement to said feed bar.

75. In a sewing machine, the combination 70 of a head having a guiding bushing at its lower end, a sliding bushing therein, a presser finger carried by said sliding bushing, a needle bar reciprocating in said sliding bushing, a top driving shaft located 75 above the top of said needle bar, independent means connecting said needle bar and said sliding bushing with the top driving shaft, the means connecting the sliding bushing including a crank-connected spring- 80 pressed piston, another crank-connected spring-pressed piston connected with said top driving shaft, a feed bar pivotally supported for rising and falling movement and connected with said last spring-pressed piston, means connected with said top driving shaft for imparting a to-and-fro movement to said feed bar, and means for raising and lowering said feed bar.

76. In a sewing machine, the combination 90 of a top driving shaft, a four-motion top feed, and means connecting said four-motion top feed with said driving shaft and including a spring and a crank-connected member 95 pressed by said spring.

77. In a sewing machine, the combination 100 of a top driving shaft, a four-motion top feed, means connecting said four-motion top feed with said driving shaft and including a spring and a crank-connected member 105 pressed by said spring, and a rock shaft also connected with said top driving shaft.

78. In a sewing machine, the combination 110 of a top driving shaft, a four-motion top feed, means connecting said four-motion top feed with said driving shaft and including a spring and a crank-connected member 115 pressed by said spring, a rock shaft also connected with said top driving shaft, a two-motion presser finger, and a spring-pressed member crank-connected with said driving shaft and said presser finger.

79. In a sewing machine the combination 120 of a top driving shaft, a needle-actuating bar connected therewith, a top feed and a presser finger having the same pivotal connection with the top driving shaft through the connection of the needle bar with said shaft.

80. In a sewing machine having a throat 125 plate, the combination of a bottom feed effective to lift the work above and clear of the throat plate when the needle is out of the work, a top feed co-operating with the bottom feed to hold the work so that the 130 work will be advanced at a uniform speed by said top and bottom feeds, a presser finger effective to engage the top of the work prior to the top and bottom feeds leaving their grip on the work and while the

needle is in the work to hold it against the throat plate, said presser finger maintaining such holding position until the feeding movement of the top and bottom feed, and 5 means for actuating the top and bottom feed and presser finger, said top feed and presser finger each having a foot, one having a slot through which the foot of the other reciprocates.

10 81. In a sewing machine having a throat plate, the combination of a bottom feed effective to lift the work above and clear of the throat plate when the needle is out of the work, a top feed coöperating with the 15 bottom feed to hold the work so that the work will be advanced at a uniform speed by said top and bottom feeds, a presser finger effective to engage the top of the work prior to the top and bottom feeds leaving 20 their grip on the work and while the needle is in the work to hold it against the throat plate, said presser finger maintaining such holding position until the feeding movement of the top and bottom feed, and means for

actuating the top and bottom feed and 25 presser finger, said top feed and presser finger each having a foot, the foot of the top feed having a slot through which the foot of the presser finger reciprocates, the foot of the presser finger constructed of a size and shape 30 to permit the free turning of the work while such presser finger is in engagement therewith and the feeds are free thereof.

82. In a sewing machine the combination of a top driving shaft, feeding mechanism 35 including a top feed connected with said top driving shaft for rising and falling movements, means for imparting a to and fro movement to said top feed, and a presser finger also connected with said top driving 40 shaft for rising and falling movement, each of said connections with the top driving shaft including a shock absorbing means.

Signed at Nyack, in the county of Rockland and State of New York, this 19th day 45 of February, 1916.

JOHN P. WEIS.
